UNITED STATES PATENT OFFICE.

TOMASZ CZERNIAWSKI, OF NEW YORK, N. Y.

SHIP-REPAIRING APPLIANCE.

1,099,167.

Specification of Letters Patent. Patented June 9, 1914.

Application filed March 19, 1914. Serial No. 825,858.

To all whom it may concern:

Be it known that I, TOMASZ CZERNIAWSKI, a subject of the Emperor of Austria-Hungary, residing at New York, in the county 5 of New York and State of New York, have invented certain new and useful Improvements in Ship - Repairing Appliances, of which the following is a specification.

This invention relates to certain new and 10 useful improvements in ship repairing appliances.

The primary object of the invention is to provide means carried by a ship and substantially below the water line thereof and 15 positionable for immediate use for covering a hole or opening formed in the hull of the ship by an accident or a collision.

A further object is to provide a compact 20 hole-repairing curtain at a point adjacent the keel of the ship and readily shiftable for inclosing substantially the entire exterior surface of the hull as an advantageous protector against the entrance of water through the hole.

25 It is further devised to provide a hull inclosing curtain positioned fully protected upon the keel portion of the ship and readily manipulated from the deck of the latter to be extended as a covering over substantially the entire hull surface and automatically guided during the unrolling operation.

With these general objects in view and others that will appear as the nature of the 30 invention is better understood, the same consists in the novel combination and arrangement of parts hereinafter fully described, illustrated in the accompanying drawings, and pointed out in the appended claims.

In the drawings forming a part of this 40 application and in which like designating characters refer to corresponding parts throughout the several views: Figure 1 is a side elevation of a ship showing my improved device upon one side thereof in its closed position. Fig. 2 is a vertical transverse sectional view thereof substantially upon line 2-2 of Fig. 1, with the device 45 positioned upon both sides of the ship, and Fig. 3 is a horizontal longitudinal sectional view upon line 3-3 of Fig. 2 with the curtains unrolled.

Referring more in detail to the drawings, the ship 10 is illustrated as provided upon both sides of the keel 11 thereof with elongated casings 12 having tapered ends 13 for

giving the same less resistance to the water during the passage of the ship therethrough. Said casings are preferably mounted opposite to each other and are secured to the keel and to the bottom keel covering 14. A 60 curtain member 15 is provided normally rolled and positioned in each of said casings 12 similar to the usual form of window-shade, the same being secured to and rolled upon the central axle or roller 16. The roller 65 of each curtain is trunnioned in any desired manner within its respective casing, as by means of bearing brackets 17 positioned within and adjacent the opposite ends of the casing while each casing is provided with a 70 top opening or slot 18 and through which the curtain 15 extends and is adapted to be unfurled by means of cables 19 secured adjacent the ends of the curtain by means of loops 20, while the other ends of said cables 75 are attached for winding upon the drums 21 mounted upon the gunwale 22 of the ship.

The curtains may be provided with springs for normally retaining the same 80 rolled upon the axles 16 although the same is not necessary to the perfect operation of the device. A dove-tailed tongue block 23 is secured to the inner face of each curtain 15 adjacent the opposite ends thereof and is slidably positioned within slidable guide- 85 ways or strips 24 vertically secured in spaced relations upon the side of the hull and whereby it will be evident that the curtain will be guided thereby in its upward movement upon the outside of the hull. 90

From this description, the complete operation of the device will be apparent.

In the event of a collision which forms a hole or break in the hull, the winding drums or windlasses 21 may be operated by the 95 crank handles 25 thereof to unwind the curtain and manually draw the same up the side of the hull, substantially inclosing the hull and extending over the hole in the side thereof. The pressure of the water upon 100 the outer side of the curtain forces the curtain firmly against the hull and closes the aperture therein against the entrance of water from without. Such repairing of the hull is deemed sufficient until the ship is 105 enabled to reach its destination for permanent repairs.

It is obvious that the present arrangement may be provided for only the main side portions of the hull or may be positioned sub- 110

stantially entirely around the same and the scope of the present invention includes such positioning of the present curtain structure.

While the forms of the invention herein shown and described are what are believed to be preferable embodiments thereof, it is nevertheless to be understood that various forms and modifications thereof may be had without departing from the spirit and scope 10 of the invention as claimed.

What I claim as new is:—

1. A device of the class described, comprising in combination with a ship hull, a rolled curtain trunnioned upon the keel thereof, means positioned upon the deck of the ship adapted for unrolling said curtain in contacting position with the hull, and guide means upon said hull for said curtain.

2. A device of the class described, comprising tapered casings having top slots therein and oppositely positioned longitudinally upon the keel of the ship, axles trunnioned within said casings, curtains mounted upon said axles and projecting through said

slots, hoisting means secured to said curtains and mounted upon the deck of the ship, and guides for said curtains extending upwardly upon the ship's hull.

3. A device of the class described, comprising tapered casings having top slots 30 therein and oppositely positioned longitudinally upon the keel of the ship, axles trunnioned within said casings, curtains mounted upon said axles and projecting through said slots, winding drums positioned upon the 35 deck of the ship, hoisting cables upon said drums having their free ends secured to said curtains, slotted ways upwardly-extending upon the sides of the ship hull, and blocks carried by said curtains and slidably 40 positioned within the slots of said ways.

In testimony whereof I affix my signature in presence of two witnesses.

TOMASZ CZERNIAWSKI.
